Term of patent 14 years

(Cl. D87—5)

Ti Q.S.

FIG. 1 is a perspective view of an illuminable vanity case, showing my new design, in closed condition;

FIG. 2 is a right-side elevational view in open condition for normal use;

FIG. 3 is a front perspective view thereof;

FIG. 4 is a rear perspective view thereof, a plain rectangular recess for a power cord being partially shown behind the mirror; and

FIG. 5 is a perspective view of the vanity case in flat opened condition.

I claim:

The ornamental design for an illuminable vanity case, as shown and described.
